UNITED STATES PATENT OFFICE.

CHARLES HORACE GILBY, OF CHRISTCHURCH, NEW ZEALAND.

SIPHON.

SPECIFICATION forming part of Letters Patent No. 739,489, dated September 22, 1903.

Application filed March 6, 1902. Serial No. 96,994. (No model.)

To all whom it may concern:

Be it known that I, CHARLES HORACE GILBY, accountant, a subject of the King of Great Britain and Ireland, residing at Christchurch, in the Colony of New Zealand, have invented a new and useful Improvement in or Relating to Siphons; and I do hereby declare the following to be a full, clear, and exact description of the same..

10 This invention relates to siphons, and has for its object to provide a siphon the outlet of which may be thrown below and above the liquid-level of the receptacle or other article from which the liquid is being drawn and at 15 the same time the liquid is held within the siphon-tube, so that when the outlet is thrown below the liquid-level siphonic action takes place without the necessity of filling the tube after every stop or providing valves. This is 20 accomplished by providing a movable device on the delivery end of the siphon-tube adapted to contain liquid to provide a seal to prevent the entrance of air to the tube when the outlet is above the liquid-level and to permit the 25 liquid to flow through the tube as soon as the outlet drops beneath the liquid-level.

The device is also employed for giving the tube the initial or preliminary filling.

In the accompanying drawings, Figure 1 is 30 a side elevation of my improved siphon; and Fig. 2 is a similar view, enlarged, showing the stuffing-box and the spout in section.

The siphon-tube A is of ordinary construction, and on the delivery or long leg thereof 35 is a sleeve B, closed at its top except for an outlet or spout C upon one side thereof. The closure of the top is effected by means of a stuffing-box D and a gland d, through which the long leg of the tube works. Means is provided for securing one leg of the siphon within an opening of a tank or the like. This means consists of a spring made out of a single strip of material bent to form a loop 1, which embraces the siphon-tube, and two 45 spring-arms, which engage and receive the walls of the opening in which they are inserted.

The spring-arms are formed by deflecting the strip upwardly and outwardly to provide

inclined walls 2, by which the arms are pressed together, thence upwardly and inwardly, and thence upwardly and outwardly to provide recesses 3, in which the walls of the opening are received. The end of one of these spring-arms is provided with an extension 4, projecting downwardly and outwardly therefrom, whereby the siphon may be hung up when not in use.

When it is desired to use the siphon, the shorter leg, with the attached spring, is inserted in an opening in a tank or the like and pressed downwardly, compressing the spring-arms together, and the short leg of the siphon is held securely in place. The outlet or spout c is then closed by placing the finger over the same, and the sleeve is drawn downwardly to exhaust the air from the tube, whereby the liquid from the receptacle then passes into the tube to fill the vacuum. The finger is withdrawn from the spout, and the outlet being lower than the liquid-level the liquid flows through the sleeve and out of the outlet. When it is desired to stop the flow and still retain liquid within the siphon-tube, the sleeve is raised until the outlet is above the liquid-level, when the liquid within the sleeve forms a seal for the end of the tube and prevents the entrance of air thereto.

Having thus described the invention, the following is what is claimed as new therein:

1. The combination with the siphon-tube, of a sleeve slidable on the delivery-leg thereof, provided with an outlet at such a point that when the said sleeve is in one position the outlet will be below the liquid-level, and when in the other position will be above said liquid-level; said sleeve being adapted to contain liquid which holds the liquid within the siphon-tube when the outlet is above the liquid-level, and permits it to flow when the outlet is below the liquid-level.

2. The combination with the tube, of a sleeve, closed at its lower end, and at its upper end except for an outlet, said sleeve being slidable on the delivery-leg of the tube, around which it forms a continuous space throughout its length, the outlet being located at a point to permit it to be lowered be-

neath the liquid-level of the tube when the sleeve is lowered, and to be raised above the liquid-level when the sleeve is raised.

3. The combination with the siphon-tube, 5 of a sleeve closed at its lower end, and at its top except for a valveless outlet, and slidable on the delivery-leg of the tube.

In testimony whereof I have signed this specification in the presence of two subscribing witnesses.

CHARLES HORACE GILBY.
